ATTORNEY

UNITED STATES PATENT OFFICE

DANIEL L. TROYER, OF CLEVELAND, OHIO

PENCIL HOLDER

Application filed April 19, 1930. Serial No. 445,730.

This invention relates to pencil holders or clips designed to attach a pencil to a pocket, lapel, or other portion of a garment.

A primary object of the invention is to so construct a device of this character that it will effectively hold the pencil in engaged position and prevent rocking movement thereof such as would tend to detach it from its support.

Another object is to provide a holder for pencils or pens which is extremely simple in construction and which may be easily and cheaply manufactured.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a rear elevation of the holder constituting this invention shown applied; and

Fig. 2 is a side elevation thereof.

In the embodiment illustrated a pencil 1 is shown to which the holder is attached. This holder which is numbered 10 is formed from a single piece of spring wire coiled intermediate its ends, preferably midway said ends, to form a pencil encircling member 11 here shown composed of two coils although obviously it may be made of more and through which the pencil 1 is designed to pass and be closely engaged thereby.

The ends of the wire from which these coils 11 are formed are wound to form a series of vertical coils 12 arranged at one side and another series 13 at the opposite side and which are designed to form winglike extensions for the holder adapted to engage the support on which the pencil is mounted and prevent it from pivoting or rotating thereon. Three coils are shown in each of the series 12 and 13 although obviously more or less may be used, if desired and the terminals of these coils are extended to form arms 14 which converge towards their free ends and are secured together at their terminals by any suitable means, a ball 15 being here shown for this purpose to facilitate the insertion of the device in the

poCKET of the user. The arrangement of the coils 12 and 13 causes the connected ends of the arms 14 to extend inward in yieldable engagement with the pencil 1 when the device is applied to form a gripping engagement therewith so that when the coat pocket or other support is inserted between the ball and the pencil the latter will be securely mounted thereon.

From the above description it will be obvious that the holder may be quickly and easily applied to a pencil by slipping the latter through the coils 11 and may be attached to a pocket or lapel or other support by insertion between the gripping member and the pencil of the portion to be engaged.

While the holder is shown applied to a pencil obviously it may be used in connection with a fountain pen or any small implement the handle of which may be inserted through the coils 11.

The arrangement of the series of coils 11 positioned horizontally and those 12 and 13 arranged on opposite sides thereof and disposed vertically provide a yieldable anti-rocking holder formed by the arrangement of the coils in planes at right angles to each other.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

1. A pencil holder comprising a piece of wire coiled intermediate its end to form a pencil receiving socket or sleeve, a clamping finger connected with said sleeve, and lateral extensions arranged between said finger and sleeve to prevent rocking of the article in connection with which the device is used.

2. A holder of the class described comprising a sleeve-like member for the insertion of the article to be held and having wings arranged at opposite sides thereof to prevent rocking of the article when being supported

by the holder, and a clamping finger carried by said wings.

3. A holder of the class described comprising a piece of wire having horizontal coils formed intermediate its ends with laterally extending coils arranged on the opposite sides of said first mentioned coils and wound to arrange their axes at right angles to the axes of the horizontal coils, said lateral coils having arms extending therefrom and converging towards each other to form a clamping element.

4. A pencil holder comprising a piece of wire coiled intermediate its ends to form a pencil receiving sleeve said wire being extended in opposite directions from said sleeve and wound to form coils having their axes extending in planes at right angles to the axis of said sleeve with the terminals of the wire extended to form arms converging towards their free ends and secured to form a clamping finger.

DANIEL L. TROYER.
